UNITED STATES PATENT OFFICE.

FRANK L. CROSS, OF PORT WASHINGTON, NEW YORK, ASSIGNOR TO CROSS PAPER FEEDER COMPANY, A CORPORATION OF MASSACHUSETTS.

SHEET-FEEDING MACHINE.

Application filed November 15, 1922. Serial No. 601,112.

The invention relates to paper feeding machines which separate individual sheets from a pile or bank and more particularly to that type of machine known as comber feeders.

In operating comber feeders, particularly on color work, it has been found desirable or necessary to blow air between the sheets at the top of the pile or, in other words, to wind the sheets in order that the sheets may be properly separated by the comber wheel. The extent to which the sheets should be separated or loosened by winding or blowing air against the edges of the bank varies with the condition of the sheets in that part of the bank being acted upon by the combers. When the sheets offer considerable resistance to separation by the combers, owing to static electricity, to atmospheric conditions or to the character or condition of the printed matter on their surfaces they require more winding and when they offer less resistance to separation due to the absence or decrease in the electricity or variation in the atmospheric conditions or character of the printed matter, they require less winding. The extent to which the sheets are fanned out or separated prior to being acted upon by the combers also affects the extent to which they should be winded. The blowers heretofore commonly utilized for winding the sheets have been constructed and arranged to deliver a continuous current of air against the upper edge of the pile at the desired point or points and have been provided with regulating valves or devices by which the operator may regulate or adjust the blast of air to suit the conditions and character of sheets in the pile being operated upon. Since the condition of the sheets may and usually does vary widely in different parts of the bank or pile during the run, these devices have not proved satisfactory and it has been necessary for the operator to continually watch the effect of the blowers on the pile and to make frequent adjustments in order to secure even approximately satisfactory results.

The present invention overcomes the objections to these prior constructions and insures the proper action of the blowers and successful winding of the successive sheets by so regulating or controlling the blowers that a blast of air is directed against the edge of the sheets during each sheet separating cycle for a period of time which is de-

pendent upon the condition of the sheets being operated on by the comber. Since the interval during which the combing wheels act on the pile in advancing the top sheets to the cut-outs which throw the combing wheels out of action varies with the condition of the sheets being operated upon by the combing wheels, it is preferred to regulate the time of action of the blower or blowers in accordance with the combing interval, so that the air blast against the edge of the sheets is reduced or shut off as the combers cease to act and is restored when the combers are again thrown into action. In the illustrated form of the invention the blower nozzle which delivers the air blast against the edge of the sheets is connected to rise and fall with the comber wheel and is so adjusted that it is lifted above the top of the pile when the comber wheel is raised and is lowered into position to deliver the air blast against the edges of the sheet at the top of the pile when the comber wheel is lowered onto the pile. This manner of controlling the blast of air delivered against the edge of the pile not only varies its action on the sheets in accordance with the condition of the pile at the point being operated upon by the comber, but the vertical movement of the blast also tends to insure the blowing of the air under every sheet in the top of the pile and thus secures a more effective separation and uniform winding of the sheets.

The preferred form of the invention is shown in the drawings in which Fig. 1 is a side elevation of so much of a paper feeding machine as is necessary to illustrate the application of the invention thereto; Fig. 2 is a plan view of the parts shown in Fig. 1 and Fig. 3 is a rear elevation of one of the blowers.

In the drawings the invention is shown applied to the automatic sheet feeding machine known as the "Cross paper feeder" having substantially the construction and mode of operation shown and described in Patent No. 812,260, February 13, 1906. In this machine a bank or pile of feathered sheets 2 is acted upon by two independently controlled comber wheels, one of which is indicated at 4. These comber wheels are lowered upon the sheets at regular intervals and each is independently raised from the pile by cut-out mechanism controlled by the front edge of the sheet when it is advanced

into position to be acted upon by the delivery rolls. The means for lowering the combing wheel upon the pile of sheets comprises a cam 6 secured to the continuously rotating cam shaft 8 and arranged to engage a roll on the end of an arm 10 which is secured to a rock shaft 12. The shaft 12 also carries an arm 14 in which is journaled a rock shaft 16. The inner end of the rock shaft 10 is connected by a link 18 with a pivoted frame 20 carrying the comber wheel 4, and is also connected by toggle links 22 with a pivoted foot 24 which is adapted to engage the top of the pile. The outer end 15 of the rock shaft is provided with an arm 26 connected by a link 28 with a lever 30 loosely mounted on the cam-shaft 8 and held in the position indicated in Fig. 1 against the tension of a spring 32 by a latch 34. 20 The latch carries the trip finger 36 adapted to lie across the path of the sheet and also carries a pawl 38 secured to the shaft 40 which carries the trip finger and arranged to be engaged with the teeth of a ratchet 25 42 on the cam shaft by the engagement of the front edge of the sheet with the trip finger. When this occurs the ratchet acts to disengage the latch so that the spring 32 straightens the toggle links 22, thus bringing 30 the foot 24 down onto the pile of sheets and raising the combing wheel into inactive position. The cam 6 raises the presser foot and combing wheel and holds them in raised position during the delivery of the sheet 35 and while the cut-out mechanism is re-set and then again lowers the combing wheel onto the pile. As thus far described the mechanism corresponds to the mechanism shown and described in the above patent. 40 In applying the preferred form of the invention to this machine a blower nozzle 44 is arranged to direct a blast of air against the edges of the sheet in the top of the pile and approximately opposite that part of the 45 pile which is being operated upon by the combing wheel. A continuous blast of air is delivered from the mouth of the nozzle which may be regulated by any suitable valve in the supply pipe to suit the character of work being done. The nozzle is so connected with the mechanism for raising and lowering the combing wheels that it is raised out of active position when the combing wheels are raised at the end of the combing interval and is returned to active position when the combing wheel is again lowered upon the pile. As shown the nozzle 44 is held in a clip 46 secured on the end of a rod 48 by a thumb nut 50 so that the nozzle 50 may be vertically adjusted or swung in or out to bring its delivery mouth into desired relation to the top edge of the pile of sheets. The rod 48 is laterally adjustable in a bracket 52 in which it is held by a set screw 54 and the bracket is in turn secured for

fore and aft adjustment on a rod 56. The rod 56 is secured in the rear end of an arm 58, the forward end of which is secured to the rock shaft 12. With the nozzle thus mounted upon the rock shaft 12 it will be raised to bring its delivery mouth above the top of the pile and thus reduce and shut off the action of the blast upon the pile when the cut-out is operated by the front edge of the sheet to lift the combing wheel and thus throw it out of action. The nozzle will be restored to active position when the rock shaft 12 is rocked to lower the combing wheel onto the pile and again throw it into action. The period of action of the blower upon the edge of the sheets will thus be regulated and determined by the combing interval, and since this interval varies with the condition of the sheets in that part of the pile being operated upon by the combers the action of the blower will be regulated in accordance with the condition of the sheets in this part of the pile. The travel of the air blast vertically of the edge of the pile will also tend to separate the edges of the individual sheets from each other so that the air will enter uniformly between the sheets and be uniformly distributed between the sheets at the top of the pile to a depth substantially corresponding to that of the action of the combing wheels.

While it is preferred to automatically regulate the action of the blower or blowers by raising and lowering the blowers as above described it will be understood that this is not essential and that the action may be otherwise reduced and increased at the end and beginning of the combing interval or that other mechanism responsive to variations in the condition of the sheets being operated upon may be utilized for regulating the action of the blower in accordance with the condition of the sheets being operated upon by the comber.

What is claimed is:

1. A sheet feeding machine having, in combination, a comber for separating and advancing the top sheets of a pile, means for blowing air against the edges of the sheets, during each sheet separating cycle, and means for automatically regulating the action of the blowing means on the sheets in accordance with the condition of the sheets being operated upon by the comber.

2. A sheet feeding machine having, in combination, a comber for separating and advancing the top sheets of a pile, means for blowing air against the edges of the sheets during each sheet separating cycle, and mechanism responsive to variations in the condition of the sheets being operated upon for regulating the action of the blowing means on the sheets.

3. A sheet feeding machine having, in combination, a comber for separating and

advancing the top sheets of a pile, means controlled by the top sheet for arresting the action of the comber, and means for blowing air against the edges of the sheets during each sheet separating cycle regulated by the 5 combing interval.

4. A sheet feeding machine having, in combination, a comber for separating and advancing the top sheets of a pile, means controlled by the top sheet for arresting the 10 action of the comber, means for blowing air against the edges of the sheet, and means for rendering the blowing means active at the beginning and inactive at the end of each 15 combing interval.

5. A sheet feeding machine having, in combination, a comber for separating and advancing the top sheets of a pile, means for lowering the comber onto the pile, means controlled by the top sheet for lifting the 20 comber, and a blower connected to rise and fall with the comber.

6. A sheet feeding machine having, in combination, a comber for separating and 25 advancing the top sheets of a pile, means for blowing air against the edges of the sheets, and means for automatically regulating the blowing means to direct a blast of air against the edges of the sheets, during each 30 sheet separating cycle for a period which is dependent upon the condition of the sheets being operated upon by the comber.

7. A sheet feeding machine having, in

combination, a comber for separating and advancing the top sheets of a pile, means 35 for directing a blast of air against the edges of the sheets during each sheet separating cycle, and means for regulating the interval during which the blast continues by the 40 combing interval of that cycle.

8. A sheet feeding machine having, in combination, a comber for separating and advancing the top sheets of a pile, means for directing a blast of air against the edges of the sheets, and means for rendering said 45 blast active at the beginning and inactive at the end of each combing interval.

9. A sheet feeding machine having, in combination, a comber for separating and advancing the top sheets of a pile, and a 50 blower for directing a blast of air against the edges of the sheets which is raised and lowered to regulate its period of action on the sheets in accordance with the condition 55 of the sheets being operated upon by the comber.

10. In a sheet feeding machine having a comber wheel and a controlling cut-out, means for successively combing the top sheets of the feathered bank into operative 60 relation to the cut-out, and means for winding the successive top sheets for an indeterminate period corresponding to the combing interval of the cycle in each case.
